[57] CLAIM

The ornamental design for a compact microscope, as shown in the drawing.

DESCRIPTION

FIG. 1 is a right-front top front perspective view of a compact microscope showing our new design;

FIG. 2 is an elevation as seen from the right side thereof;

FIG. 3 is a front elevation thereof;

FIG. 4 is an elevation as seen from the left of FIG. 3;

FIG. 5 is a top plan view thereof; and

FIG. 6 is a rear elevation thereof.
